CLAIM

The ornamental design for a compact disc display board and holder, as shown and described.

DESCRIPTION

FIG. 1 is perspective view of a first embodiment of the inventive design for a compact disc display board and holder;

FIG. 2 is a rear elevational view thereof;

FIG. 3 is a top-elevational view thereof;

FIG. 4 is a bottom elevational view thereof, illustrating the compact disc envelope of the inventive design in an extended configuration;

FIG. 5 is a first side elevational view thereof;

FIG. 6 is a second side elevational view thereof;

FIG. 7 is a perspective view of a second embodiment of the inventive design for a compact disc display board and holder;

FIG. 8 is a rear elevational view thereof;

FIG. 9 is a top elevational view thereof;

FIG. 10 is a bottom elevational view thereof, illustrating the compact disc envelopes of the inventive design in an extended configuration;

FIG. 11 is a first side elevational view thereof; and,

FIG. 12 is a second side elevational view thereof.
